ARTHUR J. WEBER AND CHARLES BUTTERFIELD, OF MIDDLETOWN, OHIO.

RECORDING PUNCH.

Application filed February 21, 1921. Serial No. 446,935.

To all whom it may concern:

Be it known that we, ARTHUR J. WEBER and CHARLES BUTTERFIELD, citizens of the United States, residing in Middletown, in the county of Butler and State of Ohio, have invented certain new and useful Improvements in Recording Punches, of which the following is a specification, reference being had therein to the accompanying drawing.

This invention relates to improvements in recording punches, having particular reference to devices of this character adapted for use by railway conductors for punching or marking cash fare receipts, or the like,—the operation of the device resulting in marking the receipt to the passenger with the amount of the cash fare paid, and in recording or indicating on the instrument the total or cumulative result of cash collections.

The object of the invention is to provide an effective check, by means of the recording punches, on cash fares, or other cash receipts and the like, whereby such transactions will be safeguarded against loss to the operating company or principals, and whereby the employee acting in the capacity of conductor or collector will be protected against unsupported claims for shortage, and the ban of suspicion which, in the absence of effective means for checking such transactions rests generally upon all employees engaged in the work, will be largely removed.

It is an object of the invention to provide an instrument of this character of simple construction, of convenient size, and easy and rapid of manipulation, upon which errors of registration cannot readily be made, and which will be incapable of fraudulent manipulation.

In the accompanying drawings, we have shown our invention in one form of preferred construction,—it being understood that the construction here shown is for the purpose of illustrating the principle or essential features of the invention and that various modifications in the details of construction and arrangement illustrated may be made without departing from the spirit of the invention.

In the drawings:

Fig. 1 is a longitudinal, vertical sectional view of the improved punch taken on the line 1—1 of Fig. 2;

Fig. 2 is a plan view of the punch with the upper portion of the casing removed;

Fig. 3 represents a cash fare receipt upon which a cash fare has been recorded with the punch;

Figs. 4 and 5 are detail views of parts of the mechanism.

As shown in the drawings, the mechanism of the instrument is enclosed in a suitable casing 1 which serves also as a supporting frame for the different units thereof. One of the punch handles 2, as here shown, is fixed to the casing, the opposite handle 3 being pivoted in the casing as at 4. A transverse slot 5, extends horizontally across the front of the casing whereby the cash receipts or the like upon which the detail marking is to be made may be inserted into the mechanism.

A totalizing register, or counter 6, is mounted in the upper portion of the front of the casing on a transverse shaft 7 the ends of which are supported in the opposite sides of casing 1,—an aperture 8 being provided in the top of the casing whereby the registrations of the counter may be conveniently read.

Also supported in the upper portion of the casing, rearwardly of counter 6, on a transverse shaft 9, is a setting or index register 10, and in the central and lower portions, respectively, of the front of the casing, adjacent the slot 5, and supported on transverse shafts 11 and 12, are the marking registers 13 and 14, either one of which may have depressed figures 0 to 9 formed in the periphery of each of its discs,—the other register having corresponding raised figures formed on the periphery of each disc, so that the two registers will function one with the other to impress an item of registration set up thereon on a cash receipt inserted therebetween through the slot 5. Each disc of the register 14 is supported independently of the other discs on a bar 42 pivoted on a common transverse shaft 43 and having its free end 44 adapted to be engaged by a pivot bar 39 for a purpose which will presently be described.

Each of the number discs of the index register 10 is provided with a gear 15 which projects through the upper casing sufficiently to afford a convenient means for manipulating the discs manually to set up the item thereon to be marked on the cash receipt by the register 13—14 and recorded

on the total register 6. Each gear 15 meshes with a gear 16, mounted on a transverse shaft 18 and having a reduction gear 17 secured thereto. Cooperating with each 5 gear 17 is a vertically operable rack 19 which is slidably supported on a guide 20 pivoted to the lower handle 3 adjacent its fulcrum 4—a pawl 21 having a retainer 22 serving to hold each rack 19 in the position 10 to which it is adjusted by manipulation of the corresponding disc of the index register 10.

Handle 3, as here shown, is provided, inside the casing 1 and rearwardly of the pivot center 4, with a plurality of vertical brackets 23 to each of which is pivoted, as at 24, a lever 25 having a vertical projection 26 adapted to contact with the lower end of one of the racks 19, and a segment 20 27 formed at its free end and meshing with an intermediate gear 28, supported on transverse shaft 29, which meshes with gears 30 and 31 respectively of one of the discs of each of the marking registers 13 and 14.— 25 there being a lever 25 and segment 27 for each of the discs of the index register 10, the levers normally being held in their neutral relation against a transverse shaft 32 fixed in the opposite walls of casing 1 30 by spring 51.

Cooperating with each of the number discs of the index register 10 is a vertically operable bar 33 having a tooth 34 formed at its upper end adapted to register with a notch or depression 35 formed in the body of the disc, the bars being supported on a transverse shaft 36 extending through clearance slots 37 and having suitable spring connections to normally hold the same in 35 raised relation with the teeth 34 in engagement with notches 35. The lower free ends 38 of bars 33 are adapted to be moved, upon manipulation of the coating discs of the register 10, into engagement with pivot bars 40 40 supported on the up-turned ends 40 of extensions 41 of handle 3, the extensions 41 being equal in number to the segment levers 25. When all the discs of the index register 45 are at zero position, the bars 33 will be 50 in normal relation, with teeth 34 engaging the notches 35 of the discs and the lower ends of the bars out of engagement with bars 39, and the ends 39 of bars 39 as shown in Fig. 1 will pass free of the ends 44 of levers 42.

Certain details of the mechanism, as 55 springs, pawls, etc., common to registering mechanism of the general character herein illustrated and described are not shown in the drawings, and it will be understood that common practice is contemplated relative to such details of construction.

Having described the detail construction, 60 we will now describe the manner of effecting registration with our improved punch.

The index register 10 is manually operable by means of the projecting gears 15, each of the number discs being independently operable to set up the item to be registered. Thus, for illustration, to set up 70 the item 1.25 to be marked on the cash receipt and added on the cumulative register, the units disc, 10^a as here shown, will be set at 5, the tens disc at 2, and the hundreds disc at 1,—thus the corresponding racks 19 75 will be moved downwardly to like extent, and the bar 33 of each disc will be moved into engagement with the corresponding pivot bar 39 and raise the ends 39 thereof sufficiently as indicated by dotted lines in 80 Fig. 1, to engage the end 44 of lever 42 when handle 3 is actuated. Upon actuation of the handle the projection 26 of the corresponding segment lever 25 will be moved into engagement with the lower end of rack 85 19 of the units disc 10^a, and in like manner, upon further actuation of handle 3, the segment levers cooperating with the tens and hundreds discs will be moved successively 90 into engagement with the corresponding racks 19. Thus the segment levers will be variably actuated according to the setting of the index register, the movement of each lever being transmitted through gears 28 to the corresponding discs of the marking 95 registers 13 and 14, and through the discs of register 13 to the cumulative register 6 by means of intermediate gears 45 which are mounted on a transverse shaft 46 supported in the casing 1. Thus, in the case of 100 the illustration, the item 1.25 set up on the index register 10 will also be set up on the marking registers 13 and 14 and will be added to the sum of the items on the cumulative register 6, as well as being recorded on 105 the cash fare receipt inserted in slot 5 between marking registers 13 and 14.

The cumulative register may be of any suitable construction of common practice including the usual means for transferring 110 one unit of registration from one disc to the next of higher order in effecting additions on the register.

To provide for restoration of the mechanism to normal without affecting the cumulative register, each disc of the register 6 except the ten-thousands disc, 6^a as here shown, is provided with an internal ratchet 48, and has a gear 47, with a pawl 49 cooperating therewith,—the gears 47 meshing direct with 115 intermediate gears 46, and pawls 49 serving as drivers for the number discs in one direction and operating idly over the ratchets 48 in the opposite direction, the number discs being operable in one direction only, the registrations on the counter are cumulative, a total registration of the items set up on the index register and recorded by the marking registers being obtained.

When handle 3 is released the same will be 130

restored to normal position by action of spring 50 thereon,—in like manner the segment levers 25 will be restored to normal by action of spring 51, and with the return movement of the segments the marking registers 13 and 14 will be reset at the zero or normal position. Also with the return movement of the segments, near the end of the movement, pawls 21 are released by a knock-out pin 20^a secured in each of the bars 20, and segments 19 being thus released, together with the discs of the index counter, are set at normal by action of retraction springs 52. The bars 42, together with the marking register 14, are set to normal position after each operation by action of springs 53.

As will be understood from the description of the recording or marking mechanism, only such of the discs of marking register 14 will be actuated for marking the receipt, as have been brought into operation by setting of the corresponding disc of the index register,—thus no ciphers will appear as the last digit of the item. Provision is made, however, for registering ciphers between digits by connecting the bars 33 one with another by pins 33^a and slots 33^b,—the free end of each pin projecting into the bottom of the slot in the adjacent bar of lower denomination. Thus when a disc is adjusted to set up an item on the register the bar 33 of the next higher order will not be affected, but all the bars of lower denomination will be moved down sufficiently by action of pins 33^a to actuate the pivot bars 39, and thus to bring into the marking operation the corresponding discs of registers 14 which will register at the zero position.

It will be obvious, of course, from the detailed description of construction and operation, that various modifications of the arrangement may be made by those skilled in the art without departing substantially from the principle and spirit of our invention. As far as we are aware our invention as it relates to the broad combination of the index register, the marking registers and the cumulative register with their interrelated mechanism is new in this art, and we wish to consider the same broadly as defined and comprehended in the appended claims.

Having described our invention, we claim:

1. In a recording punch, in combination with an actuating member thereof, an index register normally set at zero and comprising a plurality of independently operable number discs adapted to have variable amounts set up thereon, a marking register, means to place a ticket to receive an impression from the marking register, and connections between the index register and the marking register, including a part coacting with each

disc of the index register and variably operable according to the setting of the disc, whereby upon operation of said actuating member in one direction the marking register will be actuated to mark on a ticket so placed the item set-up on the index register, and upon actuation of said member in the opposite direction the index register 70 will be set at zero.

2. In a recording punch, in combination with an actuating member thereof, an index register, a marking register and a cumulative register, means for inserting a ticket 75 in the punch relative to the marking register, and connections between said registers whereby upon actuation of said member in one direction an item set upon the index register will be recorded on said ticket by 80 the marking register and added to the sum of items on the cumulative register, and upon actuation of said member in the opposite direction the index register and marking register will be set at normal.

3. In a recording punch, in combination with an actuating member thereof, an index register, a cumulative register and means to insert a ticket in said punch, and connections between said registers whereby 90 upon actuation of said member in one direction to mark the ticket an item set up on the index register will be added to the sum of items on the cumulative register and upon actuation of said member in the opposite direction the index register will be set at normal.

4. In a recording punch, in combination with an actuating member thereof, an index register and a cumulative register, and connections between said registers whereby upon actuation of said member in one direction an item set up on the index register will be added to the sum of items on the cumulative register and upon actuation of said member in the opposite direction the index register will be set at normal.

5. In a recording punch, in combination with an actuating member thereof, an index register comprising a plurality of number 110 discs each adapted to be set independently to indicate an item to be registered, a marking register synchronized with the index register and comprising two opposite registers spaced apart to receive a ticket there-between, and connections whereby upon actuation of said member an item set up on the index register will be recorded on said ticket by said marking register.

In testimony whereof, we affix our signatures.

ARTHUR J. WEBER.
CHARLES BUTTERFIELD.
